United States Patent Office

Des. 194,369
Patented Jan. 8, 1963

194,369

CROSS

Sidney S. Kampf, North Hollywood, and Abe Hoffenberg,
Long Beach, Calif., assignors to Western Manufacturing
Jewelers, Los Angeles, Calif., a partnership

Filed Aug. 14, 1961, Ser. No. 66,339

Term of patent 14 years

(Cl. D45—16)

FIG. 1. FIG. 2. FIG. 3.

FIG. 4.

FIG. 1 is a front elevational view of an ornamental cross showing our new design;

FIG. 2 is a side elevational view thereof;

FIG. 3 is a rear elevational view thereof;

FIG. 4 is a bottom view thereof;

FIG. 5 is a perspective view of the ornamental cross of the invention wherein a jewel is located in a setting at the juncture of the two arms of the cross.

We claim:

The ornamental design for a cross, substantially as shown and described.
